UNITED STATES PATENT OFFICE.

JOHN CUTHBERT, OF CHICAGO, ILLINOIS.

ELECTRICAL CONNECTOR.

1,227,588.

Specification of Letters Patent. Patented May 29, 1917.

Application filed March 8, 1916. Serial No. 82,792.

To all whom it may concern:

Be it known that I, JOHN CUTHBERT, a citizen of the United States, residing at Chicago, in the county of Cook and State of Illinois, have invented certain new and useful Improvements in Electrical Connectors, of which the following is a specification.

This invention relates to improvements in 10 electrical connectors and more particularly to a plug connector for insertion in a screw socket of the commonly used Edison type.

A well recognized disadvantage of the 15 usual form of screw plug or screw base is that it requires several complete revolutions before the end contact seats against the bottom of the socket. This is not only an annoying and time-consuming operation, but in many instances, where the plug is frequently removed and replaced, it results in a 20 twisting and knotting of the connecting cord, particularly if the cord is short and its other end fixed.

It is the object of my invention to overcome 25 the disadvantages inherent in the above described plugs.

The particular object of the invention is to provide a plug which may be firmly seated in the common type of screw shell socket by 30 pushing the plug axially into the socket and giving it a partial turn to lock it in place. The operation of inserting my improved plug in a socket is very similar to that performed in connecting an Edi-Swan plug, the 35 Edi-Swan plug being adapted, of course, for connection only with an Edi-Swan socket, whereas my plug may be used in the common type of screw shell socket.

An additional object of my invention is 40 the construction of a plug, having a body part made in one piece and which may be wired without the removal or detachment of any parts.

Other objects of my invention are to simplify 45 the construction of electrical connector plugs increasing their efficiency and reducing the cost of manufacture.

Still further objects and advantages incident to my invention will become apparent to those skilled in the art from a consideration of the following description and drawings, wherein—

Figure 1 is a side elevation of my improved plug showing a double cord connect- 55 ed thereto.

Fig. 2 is a plan view of the same.

Fig. 3 is a diametric sectional view on the line 3—3 of Fig. 2, showing the plug inserted in a socket.

Fig. 4 is a diametric section on the line 4—4 of Fig. 2, showing the plug inserted in a socket.

Figs. 5, 6 and 7 are detached perspective views of the wedge block, and the two screw sectors.

Fig. 8 is a fragmentary sectional view 65 similar to Fig. 3 showing the position occupied by the parts when the plug is removed from a socket.

Instead of building the plug up of several 70 parts, as in the common type of screw plug, the parts of which have to be separated in order to make connection with the ends of an electric cord, and after connection is made, secured together again, I have constructed my plug with a single body part of insulating material with the connecting screws so located thereon as to be readily accessible for quick wiring, without the removal of any parts.

In general the plug comprises a body part 80 of insulating material, having at its end a centrally located axially movable contact member 21, and at diametrically opposite points on its periphery metallic screw sectors or segments 22, 23 for contact with the shell 24 of a receptacle 25. The screw sectors 22, 23 are radially movable with respect to the body of the plug and are connected mechanically in such a way with the 85 axially movable center contact 21, though electrically insulated therefrom, that when the plug is seated with its inner end against the bottom of a socket the axial movement of the central contact 21 wedges the screw 90 sectors outwardly into tight contact with the socket shell 24, after which a slight rotation of the plug, screws the plug into the receptacle a sufficient distance to tightly 95 lock it in place. The farther in the plug is 100 screwed, the tighter the screw segments are forced outwardly against the socket shell.

To remove the plug the reverse operation is performed. A spring 26 serves to move the central axially movable contact inwardly, consequently drawing the screw segments radially toward the axis of the plug and out of contact with the shell, so that after about a quarter of a revolution the plug is free to be drawn axially out of the 110 socket.

The above is a general outline of the func-

tion and operation of the plug and in order that a clear understanding may be had of the preferred embodiment of my invention, which is illustrated in Figs. 1 to 8 inclusive, I will now describe the same more in detail.

The body part of the plug indicated by the numeral 20 and formed of insulating material, such as porcelain or a non-conducting composition, such as bakelite, is of generally cylindrical outline through its major portion 27, which is that part of the plug adapted for insertion within a receptacle and which I will subsequently refer to as the inner end. A sufficient distance from the inner end of the plug, so as not to interfere with the proper seating of the plug within abnormally deep sockets I have formed a projecting annular shoulder 28, beyond which the outer or rear end of the plug is squared as at 29, so that the operator may firmly grip the same with his fingers.

A diametrically disposed slot 30 of generally rectangular cross section is formed in the cylindrical body portion of the plug 27 near its inner end to receive parts of the radial movable screw segments 22, 23, and the operating device, by means of which axial movement of the central contact 21 is converted into radial movement of the two segments. Though a mechanical connection exists between the screw segments and the central connector, it is essential that there be no electrical connection, and with this end in view, I have provided a generally rectangular block 31 of insulating material, shown in perspective in Fig. 5, to serve as the connecting medium. The block is of a width substantially that of the rectangular slot 30, although its length and height are considerably less than the corresponding dimensions of the slot. Inwardly inclined slots 32—32 are cut from the upper outer corners of the rectangular block 31 to make connection with the screw segments 22, 23. Each of the screw segments comprises a vertical portion 33 having screw threads formed on its outer face to correspond with the screw threads of the receptacle shell 24. Each sector also has an inwardly extending leg 34 at right angles to the screw threaded portion projecting from the lower edge thereof, whereas at the upper edge a downwardly and inwardly inclined wing 35 is provided for engagement with the inclined slot 32—32, in the block 31. To facilitate the assembling of the device I have made one of the screw segments (that shown in Fig. 7) of a width approximately equal to the width of the slot 30 in the body part of the plug so that after the two screw segments are positioned with respect to the insulating block 31 the assembled parts may be slid into the slot from one end, the side wings 33' of screw segment 22 which ex-

tends beyond the sides of the slot 30 overlying the periphery of the plug portion 27 and serving as additional frictional surface for contact with the receptacle shell. When assembled in position it is obvious that axial movement of the insulating block 31 results, through the action of the inclined slots 32 on the wings 35, in outward or inward radial movement of the two screw segments, 22, 23.

An axial opening in which is inserted a bushing thimble 36 extends from the transverse slot 30 through to the center of the inner end of the plug, the end contact which I have heretofore referred as being designated by the numeral 21, in this embodiment taking the form of a screw, the head of which serves as a contact and the shank portion 37 of which extends through the bushing thimble 36 and into screw threaded engagement with a tapped opening 38 in the center of the insulating block 31. From this, it will be obvious that axial movement of the central contact 21 is converted into radial movement of the screw segments 22, 23, axial inward movement of the connector causing outward movement of the sectors by pressure of the upper faces of the inclined slots 32 against the inclined wings 35, the reverse spring induced movement of 95 the center contact drawing the screw segments inwardly toward the center of the body part of the plug, and out of engagement with the screw threaded shell 24.

As a means of connecting an electric cord with the plug I have provided an axial bore 39 in the outer end of the plug extending to a depth approximately equal to the depth of the squared outer portion, into which the ends of the wires may be led. Leading 100 from the axial opening 39 are two smaller bores 40, 41, which carry the individual wires to their respective terminals. The bore 40 extends on a line that would approximately intersect the inner edge of the 110 plug, terminating however in a recess 42 formed in the inner end of the plug to receive a connector bar 43, one end of which is provided with an opening through which passes the thimble 36, to which it is clamped 115 by the thimble head 44. The connector bar 43 in its other end is provided with an opening 45 registering with the wire carrying bore 40, through which the wire 46 may be passed and clamped under the rim of the connector screw 47, which takes into the connector bar 43.

To insure the outward axial movement of the contact 21 when the plug is unscrewed and to insure proper release of the screw segments 22, 23, from engagement with the socket shell, I have provided a U-shaped spring member 26, one end of which is provided with an opening to surround the barrel of the thimble 36 and underlie the con-

necter bar 43. The other end extends radially outwardly in a continuation of the recess 42 and then is turned back upon itself and provided with an opening through 5 which the shank 37 of the screw 21 takes, the free end thus underlying the head of the screw 21 and tending to resiliently press it outwardly away from the plug.

The other wire carrying bore 41 extends 10 outwardly at a greater angle to the axis of the plug than bore 40, and terminates in a recess 48 cut in the side wall of the cylindrical portion 27 of the plug at a point approximately midway circumferentially between the two segments 22, 23. An aperture 49 connects the recess 48 and slot 30, and is substantially filled by a connector strip 50 which lies against the central inner wall of the slot 30 and extends through the opening 15 49 and over the base wall of the recess 48. The connector strip 50 is held in position by a screw 51 which takes axially through the base of the opening 39 formed in the rear end of the plug and into the inner end of the 20 strip, as at 52. The outer end of the strip is provided with an opening registering with the wire carrying bore 41 and through which the wire 53 may be passed for connection with the clamping screw 54. The 25 inner legs 34—34 of the screw segments 22, 23, overlie the inner end of the connecting strip 50 making electrical contact therewith and serving as a connection between the wire 53 and the shell of the socket when 30 the plug is in place. To insure a positive connection between the inner legs 34—34 and the connector strip 50 I have beveled off the inner ends of these legs, as at 55, for engagement with a projecting wedge shaped 35 40 nub 56 on the inner end of the block 31 so that when the plug is in place and the block firmly pressed inwardly to its wedging position, the projecting nub 56 engages the beveled ends 55 of the legs 34, 34 and 45 presses them firmly against the connector bar 50.

Whereas I have illustrated and described a preferred form of my invention, it is to be understood that various other changes 50 might be made without departing from the spirit and scope of the appended claims.

Having described my invention, what I claim is:—

1. In an electrical connector plug the combination of a cylindrical body part of insu-

lating material having a transverse opening therein, a pair of oppositely positioned contact members slidably positioned in said opening, one of said members having a width less than the width of the opening for passage therethrough, the other having a portion wider than the opening to overlie the edges thereof and the exposed surfaces of said members having screw threads formed thereon, a contact positioned at the inner end of the 60 plug and axially movable with respect thereto, and a block of insulating material positioned within the opening and engaged by all the contact members for transmitting movement of the axially movable contact 65 to the slideable contacts.

2. In an electrical connector plug the combination of a cylindrical body part of insulating material having a transverse opening extending therethrough, a pair of oppositely positioned contact members each having an inturned base portion for sliding contact with a wall of the transverse opening, and an inturned angularly disposed wing, a contact positioned at the inner end 75 of the plug and axially movable with respect thereto, and a block of insulating material positioned within the opening for axial movement with the central contact, said block having angularly disposed slots 80 for engagement with the angularly disposed wings of the contacts.

3. In an electrical connector plug the combination of a relatively fixed cylindrical body part of insulating material having a 90 transverse opening therein, a pair of oppositely positioned contact members each having an inturned base portion and an angularly disposed top portion slideable transversely of the axis of the plug in said opening, a block of axially movable insulating material positioned within the opening and engaging the contact members to move the same radially when the block is moved axially and a pin carried by the block and extending axially through the plug to the inner end thereof and having a head formed on its inner end to provide a central contact.

In testimony whereof I hereunto set my hand in the presence of two subscribing 105 witnesses.

JOHN CUTHBERT.
